UNITED STATES PATENT OFFICE

JAMES E. BLALOCK, OF PACIFIC PALISADES, CALIFORNIA

PIPE WRENCH

Application filed August 21, 1928. Serial No. 301,003.

This invention relates to wrenches, and has for an object, the provision of an improved type of automatically adjustable wrench.

A more detailed object is the provision of a wrench wherein both gripping jaws are slidably mounted upon the shank, and which is provided with means for forcing the jaws together by squeezing the handle which is composed of a pair of relatively movable 10 parts.

A further object is the provision of a wrench having slideable jaws as described, the jaws being so arranged and operably connected to one of the handle sections, that when 15 force is exerted upon the handle to turn the work gripped between the jaws, an extra degree of compression of the jaws upon the work is developed, this compression being proportional to the force exerted upon the handle.

With the foregoing and other objects in view which will be made manifest in the following detailed description and specifically pointed out in the appended claims, reference is had to the accompanying drawings 25 for an illustrative embodiment of the invention, wherein:

Figure 1 is a side elevation of the wrench of my invention showing the jaws thereof in fully collapsed position.

Fig. 2 is a rear elevation, the direction of view being indicated by the arrow 2 of Fig. 1.

Fig. 3 is a view similar to Fig. 1, but showing the jaws gripping a pipe therebetween, and with a portion of the wrench broken away 35 to reduce the size of the figure.

Fig. 4 is a vertical, medial, sectional view, the plane of section being indicated by the line 4-4 of Fig. 2.

Specifically describing the invention in the most practical form of which I am at present aware, the wrench comprises a shank 6, one end of which is extended to provide a portion of the handle 7. The remainder of the handle is formed by a lever 8 comprising a U-shaped, transverse portion 9 pivoted to the shank 6 by a pin 10 rigid with the transverse portion 9 and slidably disposed within a slot 11 extending longitudinally of the shank 6, and a longitudinal portion 12 rigid 50 and preferably integral with the transverse

portion 9 and extending adjacent the handle portion 7 of the shank 6.

A pair of gripping jaws 13 and 14 are slidably mounted upon the shank 6, being provided with apertures 16 and 17 respectively, 55 through which the shank 6 is received.

The upper gripping jaw 13 is operatively connected to the transverse portion 9 of the lever 8, by preferably a pair of links 18. These links 18 are pivoted to the jaw 13 at 60 their upper ends by a pivot pin 19, and are pivotally connected to the transverse portion 9 adjacent its after end, i. e., the end adjacent which the longitudinal portion 12 is carried, by a pivot pin 21. Hence, when 65 the lever 8 is swung about its pivotal mounting 11 in that direction which reduces the distance between the two portions 7 and 12 constituting the handle, the upper jaw 13 is slid downwards upon the shank 6. 70

Similarly, the lower jaw 14 is operatively connected to the forward end of the transverse portion 9 of the lever 8. For this purpose, preferably a bifurcated link 22 is pivoted at its upper ends to the jaw 14 by a pivot 75 23, and at its lower end to the forward ends of the transverse portion 9, by a pivot pin 24. As a result of this connection, when the lever 8 is swung about its pivot 11 to move the upper jaw 13 downwards, the lower jaw 14 will 80 be forced upwards, reducing the effective distance between the jaws.

Preferably the opposed faces 26 and 27 of the jaws 13 and 14 respectively, are formed complementarily arcuate, the arcuate face 85 of the jaw 13 being concave, and the arcuate face of the jaw 14 being convex. These concave faces 26 and 27 are provided with gripping teeth 28 and 29 respectively, by means of which round objects such as pipes and bars, 90 may be readily gripped. In order to facilitate retention of the jaws 13 and 14 in gripping engagement with such round objects, the teeth 28 of the upper jaw 13, are formed so that they slope toward the shank 6, and 95 the teeth 29 of the lower jaw 14 are formed so that they slope away from the shank 6.

A spring 31 is under tension between the lower jaw 14 and a projection 32 therebelow upon the handle end 7 of the shank 6. This 100

spring tends to retain the jaw 14 in its lowermost position, resulting through the connection of the bifurcated link 22 in retaining the U-shaped, transverse portion 9 also in its lowermost position with the pin 10 disposed in the lower end of the slot 11.

In operation, the jaws 13 and 14 may be separated in order to position them upon opposite sides of the pipe 33 or other work to be gripped by separating the portions 7 and 12 of the handle. The jaws 13 and 14 may then be brought into engagement with the pipe 33 by pressing the portions 7 and 12 of the handle together, moving the jaws towards one another as described. This will force the gripping teeth 28 and 29 against the pipe 33. Now, when force is applied to the handle of the wrench in that direction which tends to move the portion 12 of the handle toward the portion 7, the tendency developed is for the transverse portion 9 to discontinue pivoting about the pin 10, and pivot about the pin 21 because of the rigid connection between the after end of the transverse portion 9 and the upper jaw 13 which is in engagement with the top of the pipe 33. This will result in forcing the pin 10 upwards a short distance within the slot 11, so that the bifurcated link 22 forces the lower jaw 14 upwards with considerable force against the pipe 33. Thus the degree of compression exerted by the jaws 13 and 14 upon the work gripped therebetween, is in direct proportion to the amount of force exerted upon the handle section 12 to turn the work, resulting in decreased tendency of the wrench to slip thereupon.

I claim:

1. A wrench comprising a shank, one end of said shank being extended to provide a handle, a pair of opposed gripping jaws slidably mounted upon the shank above the handle, an actuating lever comprising a transverse portion pivoted to and extending across the shank and a longitudinal portion extending adjacent the handle, a link pivoted at one end to the uppermost of said jaws and at the other end to said transverse portion adjacent the same end thereof as that to which the longitudinal portion is affixed, and a link pivoted at one end to the lowermost of said jaws and at the other end adjacent that end of the transverse portion of the lever opposite the point of attachment of the other of said links.

2. A wrench comprising a shank, one end of said shank being extended to provide a handle, a pair of opposed gripping jaws slidably mounted upon the shank, a lever mounted for pivotal and sliding movement longitudinally of said shank, a portion of said lever extending adjacent the handle, and means connecting said lever with said jaws to press the jaws together by squeezing the handle and lever.

3. A wrench comprising a shank, one end of said shank being extended to provide a handle, a pair of opposed gripping jaws carried by the shank, the lowermost of said jaws being slidably thereupon, an actuating lever pivoted to the shank, the pivotal connection being capable also of a limited degree of sliding movement longitudinally of the shank, a portion of said lever being extended adjacent the handle, a link connecting said slidably jaw with the lever upon the end thereof upon the opposite side of the shank from said extended portion, and a spring normally retaining said lever in its lowermost position in respect to the handle.

4. A wrench comprising a shank, one end of said shank being extended to provide a handle, a pair of opposed gripping jaws slidably longitudinally upon the shank, a lever mounted for pivotal movement on said shank, a portion of said lever extending adjacent the handle, and means connecting said lever with said jaws to press the jaws together by squeezing the handle and lever.

5. A wrench comprising a shank, one end of said shank being extended to provide a handle, a pair of opposed gripping jaws slidably upon said shank, an actuating lever comprising a transverse portion pivoted to and extending across the shank, and a longitudinal portion extending adjacent said handle, a link connecting one end of said transverse portion with one of said jaws, and another link connecting the other end of said transverse portion with the other of said jaws.

In testimony whereof I have signed my name to this specification.

JAMES E. BLALOCK.
